UNITED STATES PATENT OFFICE.

ARTHUR S. COWAN, OF BOSTON, MASSACHUSETTS, ASSIGNOR, BY MESNE ASSIGNMENTS, TO THE STAFFORD COMPANY, OF READVILLE, BOSTON, MASSACHUSETTS, A CORPORATION OF MASSACHUSETTS.

WARP STOP-MOTION FOR LOOMS.

1,394,970.

Specification of Letters Patent. Patented Oct. 25, 1921.

Application filed July 16, 1921. Serial No. 485,179.

To all whom it may concern:

Be it known that I, ARTHUR S. COWAN, a citizen of the United States, residing at Hyde Park, Boston, in the county of Suffolk, State of Massachusetts, have invented a certain new and useful Improvement in Warp Stop-Motions for Looms, of which the following is a specification, reference being had therein to the accompanying drawings.

My invention has relation to warp-stop motions for looms, and in particular to the supports, bridges, or braces which are used at intermediate points in the length of warp-stop motions, more especially in the case of looms of considerable width, to stay the transversely-extending guide-bars, retaining rods wires or bars, and back-stop bars, restrain them from excessive vibration, and keep them parallel with one another and uniformly spaced apart across the width of a loom.

It has relation, also, to the means of securing the said supports, bridges, or braces in their position of use.

Bridges or braces of the general class referred to are mounted in usual practice upon the transversely-extending elements of warp-stop motions, usually upon the guide-bars for the drop-wires. In some instances, they are mounted fixedly without capacity for adjustment transversely of the loom. The want of such capacity gives rise to inconvenience and entails expenditure of labor and time, when it becomes necessary to remedy the faulty conditions which exist in case the warp-threads immediately adjacent the bridge or brace happen to be deflected laterally thereby at one side thereof, instead of extending at both sides thereof without lateral deviation, from the loom whip-roll to the eyes of the loom-harness and the openings between the dents of the reed on the lay. In some cases bridges or braces have been mounted with capacity for adjustment transversely of a loom, but with the provisions for attachment and adjustment located below the level of the warp-threads, and at or near the middle of the width of the series of warp-threads, so that after the warp-threads are in place in the loom the said provisions are hidden by the warp-threads and can be reached only by

spreading the latter apart and passing one's hand and the necessary wrench or other tool downward between the threads. With arrangements such as last mentioned, shifting of the bridge or brace can be effected only with considerable inconvenience and with likelihood of breakage and soiling of the warps.

The invention consists in an improved combination bridge or brace, of novel construction, for the transversely-extending elements of a warp-stop motion, including the back-stop bars. Also, in improved means of securing a bridge or brace in the desired position in a loom and enabling it to be adjusted transversely of the latter.

The said combination bridge or brace comprises, in addition to an upper portion or bridge proper, a lower section or yoke-member, connected with the lower portion of the bridge proper, formed with recessed seats for the back-stop bars, and preferably constructed to form an intermediate support or guide for the horizontally reciprocating feeler-rod or rods.

The improved securing and positioning means comprises a rod secured to the bridge or brace, extending transversely of a loom parallel with the guide-bars, etc., and a bearing or guide occupying a fixed position, which receives within it the said transversely extending rod, and holds the latter and the bridge or brace in place with capacity for transverse adjustment. In the more complete embodiment of the features of the invention the holding means and the outer end-portion of the rod are located at one end of the warp-stop motion, at a point where they are accessible from beyond the warp-threads without necessity for parting the warp-threads and passing one's hand or a tool through between them. This enables adjustments to be made conveniently, and without breakage or soiling of the warp-threads. Preferably, the said holding means is located outside of the series of warp-threads, clear of the latter.

Illustrative embodiments of my invention are shown in the accompanying drawings, in which:

Figure 1 is a side view of a portion of a four-bank warp-stop motion, showing an adjustable bridge or brace of novel con-

struction, and means of my invention for altering and securing the position thereof.

Fig. 2 is a plan view of the same.

Fig. 3 is a view of the right hand end, 5 partly in vertical section on line 3, 3, of Fig. 1.

Fig. 4 is a view in section on the line 4—4 of Fig. 1.

Fig. 5 is a side elevation of the bridge or 10 brace, proper, and Fig. 6 shows the lower section or yoke by which the transversely-extending back-stop bars are engaged, etc.

Fig. 7 shows a modified means of adjustment.

Fig. 8 shows a construction which enables 15 the position of an intermediate bridge or brace to be adjusted from either side of a loom.

Fig. 9 shows one of the friction clamps of 20 Fig. 8.

Fig. 10 shows a construction in which the adjusting-rod is screw-threaded and is fitted to a screw-threaded bearing on an end-plate of the warp-stop motion mechanism.

Having reference to the drawings,—

Aside from the features involved in the invention, the warp-stop motion illustrated in the drawings is of old design. By way of briefly describing the same, it may be stated that in practice the end-plates 1 at 30 the opposite ends of the mechanism are mounted upon the loom-frame and support the ends of the transverse bars 2, 2^a, and tie-rod 2^b, which serve as guides for the drop-wires 3, 3, the bars 2 and tie-rod 2^b also serving as rests for the warp-threads *w*, Fig. 4, occupying the slots in the lower portions of the drop-wires. The said end-plates also support the ends of the wires

40 4, 4, extending lengthwise of the respective banks of drop-wires, through the slots in the upper portions of the drop-wires, and serving to limit the descent of the drop-wires when the latter are permitted to drop in consequence of the breaking or slackening 45 of the warp-threads. In this instance, for the reception of the said ends of wires 4, 4, open-topped slots 1^a, 1^a, are made in the upper portions of the end-plates, the lower

50 ends of these slots constituting seats in which such wire-ends rest normally. Secondary seats 1^b, 1^b, at higher points at the sides of slots 1^a, 1^a, are designed to receive the ends of the wires when the latter have

55 been raised so as to lift their drop-wires *en masse* clear of the path of the feeler-rods 6, 6. In bearings 41^b in connection with the two end-plates is mounted the oscillating rockshaft 8 having fixed upon each of its

60 ends an arm 8^a having a slot 8^b receiving a stud or pin 7^a projecting from a bar 7 which is engaged with the corresponding ends of the feeler-rods 6, 6. The end-positions of the feeler-rods slide in a horizontal 65 slot 1^c in each of the end-plates, as the

feeler-rods are reciprocated back and forth below the lower ends of the drop-wires through the oscillating movement of the rockshaft 8, the outer portion of which is supported by a supplemental bearing 8^c 70 provided in an arm 8^d attached to a stud 8^e screwed into a nipple 1^d projecting from the adjacent end-plate. The said rockshaft 8 is given a constant rocking motion through connections (not shown) with some 75 convenient moving part of the loom. The back-stop bars 21, 21, 21, are supported in place below the level of the path in which the feeler-rods reciprocate, by having their ends entered into notches in the lower edges 80 of the end-plates, and held in such notches by means of plates 22, 22, Figs. 1 and 3, fastened to such edges by means of bolts 23, 23. The general construction and mode of operation of the parts thus far referred 85 to are well-known. The features of the invention, for convenience, are shown applied in connection therewith, but are equally applicable in connection with warp stop-motion mechanisms differing in general construction.

The novel bridge or brace shown in the drawings comprises a main section or body 5 and a lower section 9. The main section or body 5 is shown separately in Fig. 5. 95 The general construction thereof may vary in practice. In this instance, it has in its lower edge open-bottomed slots 5^b and 5^c to fit the guide-bars 2 and 2^a, and it has also holes 5^a, 5^e, to receive the tie-rod 2^b 100 and the shaft 8. In this instance, also, the top of the section 5 is formed with open-topped slots 5^a and elevated seats 5^b, corresponding with the slots 1^a and seats 1^b of the end-plates, and designed to receive and 105 support intermediate portions of wires 4, 4. The features of the main section, thus far mentioned, are not material to the invention. The lower section 9 is shown separately in Fig. 6. It is in the form of a bar 110 having in its upper edge open-topped slots 9^a, 9^a, to receive intermediate portions of the back stop-bars, the bottoms of such slots constituting seats for such portions of the 115 said bars. Holes 9^b, 9^b, are made in the opposite end-portions of section 9, and like holes 5^h, 5^h, are made in downward extending lugs or projections 5^g, 5^g, at opposite ends of the main section or body 5. After 120 the two sections have been fitted to the transversely-extending elements of the warp-stop-motion mechanism, they are fastened together by means of bolts 51, 51, fitted to the registering holes 9^b and 5^h. The lower section 9 is in the nature of a tie-bar connecting together the opposite downward extensions of the upper section or bridge proper.

The top surfaces of the portions of section 9 which intervene between the open-topped 130

slots 9^a, 9^a, are flush with the tops of the back-stops-bars 21, 21, when the latter are in place within such slots. Consequently, the said top surfaces and the said tops constitute a race or guideway on which the intermediate portions of the feeler-rods 6, 6, slide or roll in the reciprocating movements of the feeler-rods.

My means of securing a bridge or brace in the desired position transversely of a loom, comprises a transversely-extending rod 11 and a bearing or guide by which such rod is held. The rod is connected with the bridge or brace by any suitable means, as by forming a hole 5^c, Fig. 5, in the bridge or brace, inserting the rod into such hole, and making the rod fast with the bridge or brace by means of collars or nuts 11^a, Figs. 1, 2 and 4, upon such end at the opposite sides of the bridge or brace. In the case of plain collars, they will be secured in place upon the rod by suitable clamping screws. In case nuts are employed, the rod will be screw-threaded to receive them, as in Figs. 1 and 2. The rod 11 extends transversely of the loom, parallel to the transversely-extending elements of the warp-stop motion, and at a level below the warp-rests constituted by the tops of the guide-bars 2, 2, and tie-rod 2^b. I combine the rod with the bearing or guide in such manner that the rod may be adjusted widthwise of the loom in order that the bridge or brace may be shifted in such direction.

The provisions for holding the rod in position endwise, and for enabling it to be adjusted endwise, may vary in practice, and the location of the bearing or guide and of the said provisions widthwise of a loom may be varied. Most advantageously the said parts are located and arranged so that the provisions for securing and adjusting the rod, and thereby positioning the bridge or brace, are accessible from a point at one side of the series of warp-threads, so as to enable the parts to be reached and manipulated without it being necessary to pass one's hand or a tool down through the warp-threads. Figs. 1, 2 and 3 show a convenient type of construction comprising a bearing or guide constituted by a lug 12 formed upon one edge of an end-plate 1, bored to accommodate the rod 11, which passes therethrough, and a clamping thumb-screw 13, applied to a threaded hole that is tapped through the said lug at right angles to the bore therethrough, and engaging by its inner end against the rod to clamp the latter so as to hold it from endwise movement. The rod is of a length suitable to extend through the bearing or guide and project outward beyond the latter. With this construction, an adjustment of the bridge or brace is made by loosening the thumb-screw 13, taking hold of the outer end-portion of the rod, and

pushing or pulling the rod endwise to give the bridge or brace the desired position widthwise of the loom. The thumb-screw is then tightened up to clamp the rod and retain the bridge or brace in the position which has been given to it.

In the case of the modified means of adjustment that is shown by Fig. 7, the outer portion of the rod 11 is screw-threaded and nuts 14, 14, are mounted thereon at opposite sides of the bearing or guide 12. These nuts hold the rod and bridge or brace fixed in the desired position of adjustment, and may be utilized in obvious manner in effecting adjustment.

The rod may be extended from one end of the warp stop-motion mechanism to the other thereof, as in the case of rod 11^b in Fig. 8, in which case it usually will be mounted in bearings or guides 12^a, 12^a, upon the opposite end-plates 1, 1. In such case it may be manipulated from either side of the loom by taking hold of the corresponding end thereof. Clamping means on the order of those shown in Figs. 1, 2, and 7, 90 may be employed, but I have shown in Fig. 9 a friction clamp made by providing one of the bearings or guides, 12^a, with a friction block, 12^b, acted upon by a screw, 13^a, and arranged to bear against the rod. The friction due to the pressure and contact of the friction block will hold the rod and bridge or brace in the position in which they may have been set, but the bridge or brace may be adjusted as required by causing the rod to slide through the friction clamp.

In the case of the construction shown in Fig. 10, the rod 11 is screw-threaded in the portion 11^a thereof which passes through the bearing or guide 12^a, which latter is internally threaded so as to constitute a fixed nut, the inner end of the rod being engaged with the bridge or brace in a well-known manner permitting the rod to turn 110 relative to the bridge or brace while compelling the bridge or brace to move transversely in unison with the rod. A hand-wheel 11^c upon the rod facilitates the operation of turning the same, and through such 115 turning of the rod and the consequent endwise movement thereof as it is screwed inwardly or outwardly through the bearing or guide 12^a the bridge or brace is adjusted transversely.

What is claimed as the invention is,—

1. In a warp-stop-motion mechanism for looms, the combination with one or more reciprocating feeler-rods, the back-stop-bars, and transversely-extending elements above said bars, of an intermediate bridge or brace comprising an upper section engaging and supported by the latter elements, and a lower section supported by said upper section, having recessed seats receiving the 130

- 4
- back-stop-bars, and having adjacent such seats surfaces which conjointly with the tops of the back-stop-bars constitute a race or guideway for the feeler-rod or rods.
5. 2. In a warp-stop-motion mechanism for looms, the combination with one or more reciprocating feeler-rods, back-stop-bars, and transversely-extending elements above said bars, of an intermediate combination bridge 10 or brace comprising an upper section engaging and supported by the latter elements, and a lower section supported by said upper section, comprising a tie-bar attached by its ends to the upper section and having recessed seats receiving and supporting the back-stop-bars.
15. 3. In a warp-stop-motion for looms, the combination with transversely-extending elements thereof, and a bridge or brace for such elements, of securing and adjusting means comprising a transversely-extending rod connected with the bridge or brace and by movement of which the bridge or brace is adjusted transversely, and a bearing or 20 guide which holds said rod.
25. 4. In a warp-stop-motion for looms, the combination with transversely-extending elements thereof, and a bridge or brace for such elements, of securing and adjusting means comprising a transversely-extending rod connected with the bridge or brace and by movement of which the bridge or brace is adjusted transversely, and a clamp which 30 engages said rod to thereby hold the bridge 35 or brace in place.
35. 5. In a warp-stop-motion for looms, the combination with transversely-extending elements thereof, of an intermediate bridge or brace for the said elements, and means 40 for adjusting and fixing the position of said
- bridge or brace from a point at one side of the warp-threads.
6. In a warp-stop-motion for looms, the combination with transversely-extending elements thereof, of an intermediate bridge 45 or brace for the said elements, a transverse rod secured to said bridge or brace and extending outwardly therefrom beyond the warp-threads, and means at one side of the warp-threads for fixedly holding said transverse rod, and thus the said adjustable bridge or brace, in the desired position.
7. In a warp-stop-motion for looms, the combination with transversely-extending elements thereof, of an intermediate bridge 50 or brace for such elements, and an adjustment rod for such bridge or brace extending outward to a position accessible from beyond the edge of the warp.
8. In a warp-stop-motion for looms, the combination with transversely-extending elements thereof, of an intermediate bridge or brace for such elements, and an adjustment rod for such bridge or brace, having an end thereof located outside beyond the 55 edge of the warp.
9. In a warp-stop-motion for looms, the combination with transversely-extending elements thereof, and an end-plate thereof provided with a rod-bearing or guide, of an 60 intermediate bridge or brace for such elements, and an adjustment rod connected with such bridge or brace and extending through the said rod-bearing or guide.
